ATTORNEY

UNITED STATES PATENT OFFICE.

WILLIAM H. RICHARDS, OF PITTSBURG, PENNSYLVANIA.

RATCHET-DRILL.

SPECIFICATION forming part of Letters Patent No. 231,361, dated August 17, 1880.

Application filed November 25, 1879.

To all whom it may concern:

Be it known that I, WILLIAM H. RICHARDS, of the city of Pittsburg, in the county of Allegheny and State of Pennsylvania, have invented new and useful Improvements in 5 Ratchet-Drills, of which the following is a specification.

The invention relates to drills for metal, the motion of which is communicated by vibrating 10 a hand-lever.

The nature of my invention consists in the construction and arrangement of the parts of 15 a ratchet-drill, and also its application as a stationary hand drill-press, as will be more fully set forth.

The object of my invention is to make the 20 tool stronger, more compact, and avoid the clogging by dust, &c., and the disarrangement of parts, and at the same time secure as nearly uniform motion as possible.

In order that others may be enabled to make and use my invention, I will now describe its construction and operation, referring to the drawings connected herewith, in which—

25 Figure 1 presents a side view or elevation. Fig. 2 is a view of the spindle, showing internal working parts, and is partly in section. Fig. 3 is an end view of one of the covering-sleeves.

30 Like letters of reference refer to like parts in all these figures.

The illustration here given is that of a stationary hand drill-press; but by removing its supports and supplying a temper-feed, it can 35 be used as the ordinary ratchet-drill is, as more fully set forth in the patent dated December 4, 1877, and numbered 197,896, granted to me, upon which the improvements herein set forth have been made.

40 A is the shaft or spindle passing through the center of the standard E, and having at the lower end the head provided with the socket O for the reception of the drill. A is also pierced by two oblong holes, c', through 45 which the key-pins b' b' pass, securing thereby the movable ratchets C C. These holes c' must allow so much play to the keys b' b' as will permit the ratchets to press toward the center E the spiral springs F F, and thus dis- 50 engage themselves from their mates on the hubs of the bevel-pinions B B, as they alter- nately require to do.

The crab-teeth of the two sets of ratchets are inclined in opposite directions, so the vibrating motion of the lever R, attached to the main wheel K, acting through the ratchets on the pinions B B, causes an almost continuous rotary motion of A. 55

The lower pinion B rests upon the shoulder of the socket-head, and the other parts 60 follow in their respective positions above it, all allowing a free revolution of the spindle, the two ratchets C C, secured by the key-pins b' b', passing through the oblong holes c', conveying the motion to A. These parts are all 65 covered by the two sleeves H H, one end of which rests on the center standard, E, and the other end abuts against the inner surface of the pinions B B, thus forming a complete covering for the small working parts, preventing 70 clogging by dust, making it impossible for the pinions to get out of gear, and retaining the spiral springs F F in the best position for work. Besides adding greatly to the strength, they give a finish to the machine. 75

The sleeves are provided with oil-holes d' d', for lubricating the internal parts.

The whole arrangement is held in place by the collar G, secured by the set-screw a'.

The main wheel K moves freely on the stud 80 on one side of E.

On the top of the spindle is the balance-wheel J, intended to be of such weight that it will, by its impetus, when in motion, overcome the slight dead-point caused by the vibratory motion of K, and thus give a continuous motion to the drill. 85

The key-pins b' b' are riveted tight in the ratchets C C, but work freely in the oblong holes c'. 90

The whole machine is attached by supports L L L and bolts N N N, or their equivalents, to the post P.

The vibrating of the lever R causes the pinions B B to revolve in opposite directions alternately, one working upon the spindle A while the lever is going down, and the other when it is going up, the springs and ratchets alternately relieving themselves as the motion is reversed, while the balance-wheel equalizes 95 the motion. 100

The miter-wheel M is shown hereon as illustrating the means by which a continuous rotary motion may be conveyed from this to other

machines, such as meat-choppers, feed-cutters, &c.

Having thus fully described my invention, what I claim is—

5 The combination of the spindle A, having oblong holes c' , and provided with the balance-wheel J, the ratchets C, with pins b' , the springs F, center E, collar G, covering-sleeves

H, and supports L, all constructed and arranged substantially as and for the purposes ¹⁰ herein set forth.

WILLIAM HY. RICHARDS.
